ABSTRACT

Destructive hydrogenation of lubricating oils by hydrogenating, hydrocracking and isomerizing oils, which have not been conditioned, in the presence of at least two layers of catalysts in a single reaction, to obtain a synergistic effect of their hydrogenating, hydrocracking, and isomerizing functions.

PROCEDURE AND REACTOR FOR DESTRUCTIVE HYDROGENATION OF LUBE OILS

FIELD OF THE INVENTION

The present invention refers to a procedure and reactor for the destructive hydrogenation of lubricating oils, in order to obtain lubricants, in one or more cuts, having a high viscosity index.

BACKGROUND OF THE INVENTION

There are known methods of improving the quality of lubricating oils by the selective extraction of a feedstock. These methods mostly used today in petroleum processes have a limited capacity for economically increasing the viscosity index. In the petroleum industry, the quantity of wax-free crude oils, which is not suitable for obtaining premium grade lubricating oils, is continually increasing. Obtaining oils having a high viscosity index from these crude oils by the methods of selective extraction is quite impossible.

Other known methods of improving the quality of lubricating oils involve hydrofining the feedstocks treated with hydrogen. These methods, however, do not change the viscosity index of the processed products. The catalysts used in the hydrofining processes do not have a cracking function, so that, as a rule, the aromatic hydrocarbons are not changed into condensed naphthenes, which should be hydrocracked selectively in order to produce alkyl-naphthenes with a high viscosity index. Also, these catalysts do not isomerize the paraffin hydrocarbons.

There are known methods of destructive hydrogenation of lubricating oils, applied recently in industry, which eliminate selective extraction and hydrofining, and achieve yields more or less comparable with the latter, changing the distilled oils into oils with a high viscosity index, without conditioning the feedstock. These methods are based on contacting the feedstock with the hydrogen on a layer of specific catalyst which has the same structure along the whole reaction zone. However, the methods of destructive hydrogenation of lubricating oils do not achieve a significant increase in the viscosity index at a high yield; a steady average increase in this characteristic is difficult to obtain since only one catalyst is used in the reactor, thus not creating the possibility of an synergistic action of the functions of hydrogenation, hydrocracking and isomerization in the reactor, in the presence of the appropriate catalysts.

DESCRIPTION OF THE INVENTION

Destructive hydrogenation of lubricating oils, according to the invention, eliminates the above disadvantages and achieves relatively high yields of hydro-treated products with a substantial increase in the viscosity index, without conditioning of the feedstock, by means of two or more distinct layers of two specific and different catalysts, set out in the same reactor; the first catalyst has the prevalent function of hydrogenation, and the second one has the prevalent function of hydrocracking-isomerization, functions that are carried out in relation to the active element composition of the catalysts and/or acidity of their support ensuring taking over of heat from the reaction of hydrogen and/or hydrocarbon fractions. The reactor for this procedure is a cylindrical vessel made up of two or more successive reaction zones in which there are two or more suc-

sive and distinct layers, even or uneven, formed of two catalysts, specific or different. Separating the zones are one or more sieves of the fractionating-tray type without downcomers; a coaxial cooling system formed of two or more pipelines for feeding every reaction zone in the cooling point, with hydrogen and/or hydrocarbon fractions is also provided.

DESCRIPTION OF THE DRAWING

- 10 FIG. 1 is a schematic diagram of the reactor operating with only two catalyst layers;
 FIG. 2 is a graph showing results obtained.
 FIG. 2 represents the variation of the viscosity index and the viscosity of hydrogenated oil, obtained in accordance with the invention (curves —□— and —*—), as compared to the same elements obtained with type A catalysts (curves -0-) and —. —) and B type (curves —Δ— and —+—) catalysts when used separately in the reactor. Catalyst A is a nickel-molybdenum catalyst, and catalyst B is a nickel-tungsten catalyst. By proper selection of the operating conditions, at the same yield of oil, the viscosity index of the oil resulting from the invention is, in all cases, higher than when type A and type B are used separately; in addition, at the same viscosity index, the highest yields result when following the procedure of this invention.

SPECIFIC DESCRIPTION

- 30 The reactor is made up of a pressurizable vessel 1 in which there are two catalyst layers A and B, a separating sieve 2 between catalyst layers A and B, a pipeline 3 for feeding hydrogen or hydrocarbon fractions to the cooling point of the catalyst layer A and a pipeline 4 for feeding hydrogen or hydrocarbon fractions to the cooling point of the catalyst layer B.

SPECIFIC EXAMPLES

Example 1

- 40 The feedstock, a distilled oil of naphthenic-aromatic type, having the viscosity: 30°E/50°C and viscosity index: 45, together with the addition and recycle of hydrogen, is fed to the reactor with a space velocity of 0.5 vol.vol. hr., under a pressure of 175 atm. and a recycle ratio of 1500 m³/m³ STP and are passed downflow through two distinctive layers of specific and different catalysts of A and B type. Thus are obtained the improvements of the viscosity index, decoloration, sweetening, denitrification, carbon residue reduction, and demetallization. Cooling of the reaction zone is done with hydrogen. After the rich gases have been removed from the reaction product, the liquid product is stripped in order to remove the hydrogen sulphide and gases, and then fractionated to separate the light and medium products. The bottom product lubricating oil is then vacuum-distilled in order to obtain different qualities of oils.

- 50 60 The lubricating oil fraction obtained when operating at 415°C temperature has the characteristics given below in Table 1.

TABLE 1

	Characteristics	Values
65	Yield, % wt. (oil within the same distillation range as the feedstock)	66

TABLE 1-Continued

Characteristics	Values
Viscosity Index	100
Viscosity, °E/50°C	6.4

EXAMPLE 2

The same feedstock is used under the same conditions as above at the reaction temperature of 420°C.

The unit lubricating oil fraction obtained has the following characteristics:

TABLE 2

Characteristics	Values
Yield, % wt.	62
(oil with the same distillation range as the feedstock)	
Viscosity index	102
Viscosity, °E/50°C	6.2

EXAMPLE 3

In order to compare the results of the invention to those of the known methods, the same feedstock was used under the same conditions at two different reaction temperatures, but only one layer of the same specific type A or type B catalyst was introduced in the reactor. The results are shown in Tables 3 and 4.

TABLE 3

With A-type catalyst			
Temperature, °C (reaction)	420	435	
Yield, % wt.	70	50	
(oil with the same distillation range as the feedstock)			
Viscosity index	86	100	
Viscosity, °E/50°C	9	5.8	

TABLE 4

With B-type catalyst			
Temperature, °C (reaction)	420	42	
Yield, % wt.		42	
(oil with the same distillation range as the feedstock)			
Viscosity index	100		
Viscosity, °E/50°C	4.3		

Table 5 shows that the procedure followed according to the invention yeilds a product of the highest viscosity, at the lowest operating temperature for an oil of viscosity index of 100.

TABLE 5

Characteristics	Values		
With A-type catalyst	With B-type catalyst	As per invention	
Reaction	435	420	415

TABLE 5-Continued

5	Characteristics	With A-type catalyst	With B-type catalyst	As per invention
10	Yield, % wt. (oil with the same distillation range as the feedstock)	50	42	66
15	Viscosity, °E/50°C	5.8	4.3	6.4

By a proper selection of the operating conditions, at the same yield of oil, the viscosity index of the lubricating oil is, in all cases, higher than in the cases where A and B type catalysts are used separately, and at the same viscosity index, the highest yields are also obtained in the case of the procedure as per invention.

The procedure and reactor, according to the invention, have the following advantages:

They lead to a synergistic action of the catalysts employed so that a higher viscosity index is obtained at relatively high yields of product.

High-quality products should be obtained under milder conditions.

They offer the possibility of guiding the reactions so that depending upon the quantity, activity and selectivity of the catalysts employed, premium grade products can be obtained as required.

We claim:

1. A process for the destructive hydrogenation of a lubricating oil comprising the steps of:

selectively hydrogenating polycyclic aromatic compounds in the lubricating oil by passing same in the presence of hydrogen at a temperature of about 410° to 440°C and a pressure of about 150 to 180 Atm downwardly through a nickel-molybdenum first catalyst layer in a reactor;

passing in the same reactor the selectively hydrogenated lubricating oil through a nickel-tungsten second catalyst layer distinct from the first at a temperature of about 410° to 440°C and at a pressure of 150 to 180 Atm; and without separation of the reaction product obtained upon passage of the lubricating oil through the first layer for the hydrocracking and isomerization of components of the lubricating oil; and

stripping gases from the reaction product emerging from the second layer and fractionating the liquid phase thus recovered.

2. The process defined in claim 1 wherein hydrogen is recovered from said reaction product in the stripping of gas therefrom and is recirculated to the hydrogenation of the lubricating oil at a recycle ratio of about 1,500 m³ (STP) per m³, the oil being provided at said first layer at a space velocity of 0.5 to 1 volume/hour/reactor volume.
